FOREIGN PATENT DOCUMENTS

WO WO2013019937 A1 2/2013

Primary Examiner — Carla J Wright*(74) Attorney, Agent, or Firm* — Adler Pollock & Sheehan P.C.; Daniel J. Holmander, Esq.(57) **CLAIM**

The ornamental design for a cell phone case, as shown and described.

DESCRIPTION

FIG. 1 is a front elevation view of a cell phone case showing my new design;

FIG. 2 is a top view thereof;

FIG. 3 is a front perspective view thereof;

FIG. 4 is a front elevation thereof, showing two lower elements of the cell phone case in an alternate configuration; FIG. 5 is a front perspective view thereof, showing two lower elements of the cell phone case in an alternate configuration;

FIG. 6 is a second front perspective view thereof, showing two right-side elements of the cell phone case in an alternate configuration; and,

FIG. 7 is an exploded front view thereof, showing four elements of the cell phone accessory separated from the underlying rear portion of the cell phone case for clarity of disclosure.
